Baldwin Wright

UNITED STATES PATENT OFFICE.

FREDERICK TROUTON SMALL, OF SPONDON, NEAR DERBY, ENGLAND, ASSIGNOR TO AMERICAN CELLULOSE AND CHEMICAL MANUFACTURING COMPANY LIMITED, A CORPORATION OF DELAWARE.

REGULATING VALVE FOR ARTIFICIAL-SILK SPINNING APPARATUS.

Application filed February 5, 1923. Serial No. 617,110.

To all whom it may concern:

- Be it known that I, FREDERICK TROUTON SMALL, a subject of the King of Great Britain, of Spondon, near Derby, England, have invented certain new and useful Improvements in or Relating to Regulating Valves for artificial silk spinning apparatus, of which the following is a specification.
- 10 This invention relates to regulating valve apparatus of pumping apparatus of the kind wherein two pumps of the gear wheel or other type are arranged in series, and are so constructed or operated that the delivery of the first or main pump is greater than the delivery of the second pump which receives liquid therefrom, and which thus acts as a measuring device to pass the quantity of fluid required per unit of time, the 15 surplus liquid from the first pump passing through a branch conduit on the connection between the two pumps to one side of the diaphragm valve, the other side of which is exposed to the pressure of the delivery pipe 20 of the second or measuring pump, so that according as the pressure in the pipe or connection between the two pumps or that in the delivery from the second pump predominates, the diaphragm, by means of a 25 needle or like regulating device which it carries, acts to enlarge or reduce an opening or by-pass through which excess liquid in the branch pipe can escape back into the main supply to the first pump, the pressure 30 between the two pumps being thus kept equal to that in the delivery pipe from the second pump, so that equal pressures are maintained on both sides of the second or measuring pump, and if the delivery pressure 35 from this pump varies, the diaphragm valve automatically adjusts the inlet pressure to the same degree. Such apparatus is described in British patent specification No. 182,154.
- 40 In such pumping apparatus, which are employed for supplying the spinning solution to the nozzles or jets of artificial silk spinning installations, the regulating diaphragm valve is usually arranged horizontally.
- 45

In operation with such apparatus certain difficulties have been found to occur in practice.

These difficulties are due firstly to the accumulation of air, during operation, in the upper chamber of the diaphragm valve, namely that in which the orifice or by-pass controlled by the needle or like device of the diaphragm is situated. Secondly the needle or like device of the diaphragm, being fixed positively to the diaphragm, is liable to break in action, this being mainly due to the difficulty of centering the needle or the like in the valve; thirdly the flat plate type of diaphragm may fail to seal the by-pass when required, this being often due to grit keeping the two faces apart.

According to the present invention we make the upper chamber of the diaphragm valve that serves to maintain the pressure between the two pumps equal to that of the delivery from the second pump dome-shaped or upwardly dished, the highest point being the outlet or by-pass, and I employ a loose or floating valve inserted between the diaphragm and said by-pass outlet. With such an arrangement it is found that air which may be present in the valve chamber or pass into the valve chamber with the liquid can escape immediately the valve is opened by the needle or the like, owing to the location of the by-pass orifice in the top of the domed upper chamber, and the needle valve can also locate itself automatically, because it is free to move. It may be constructed and arranged so that its apex never falls below the valve seat or other valve supporting member. A coil, leaf or other suitable spring is preferably provided between the needle and the valve seat to ensure that the needle operates automatically with the diaphragm.

The accompanying drawings illustrate by way of example one form of diaphragm valve comprising all the before mentioned improvements, Fig. 1 being a vertical section and Fig. 2 a plan of the valve.

In this form the valve casing is made in upper and lower circular portions 1, 2 fixed together by screws 3 to clamp between them.

the rim of a diaphragm 4 of phosphor bronze or like corrosion resisting material, which divides the interior of the valve casing into upper and lower chambers 5 and 6. The under face 1^a of the upper portion of the valve casing is made of shallow dome shape as shown. 7 is a by-pass union opening through the centre of the crown of the upper valve chamber 5 by its passage 8 and 10 adapted to be connected to a pipe or conduit leading back to the supply side of the first pump or pump of greater delivery as before mentioned. 9 is a union opening into the valve chamber 5 at 10 and adapted for 15 connection to the branch before referred to from the connecting pipe or conduit between the two pumps, that is to say the branch through which the surplus liquid from the first pump passes to the diaphragm 20 valve.

A tubule 11 opening into the lower valve chamber 6 serves for connection to the discharge outlet of the second or measuring pump before mentioned, and a tapped discharge outlet 12 from the valve chamber 6 serves for connection to the delivery pipe to the artificial silk spinning nozzle. A loose or floating needle valve 13 is placed on the diaphragm 4 so as to open and close the 25 by-pass orifice 8 according as the diaphragm moves under the action of the opposing pressures on the faces of the diaphragm, viz, that in the connection between the two pumps, and that on the delivery side of the 30 second pump. A coiled spring 14 is fitted between the crown of the dome and the base of the needle valve which is formed by a circular plate or disc 13^a resting on the diaphragm, this base 13^a of the needle valve 35 being slightly dished to fit snugly on the slightly dished diaphragm, thereby assisting in preventing fluid from tending to separate the needle valve and the diaphragm.

15 represents a screw plug provided on 45 the top side of the valve casing, and which is removed on starting to allow all the air to escape quickly from the inside of the valve chamber. This operation is performed when first passing the spinning solution 50 through the valve, to ensure that it is completely flooded on starting.

It will be seen that owing to the location 55 of the by-pass outlet 8 in the crown of the domed upper valve chamber 5, any air which in operation may be present in the valve chamber or pass with the liquid into the valve chamber, can escape through the by-pass immediately the valve is opened by the needle. Also the loose floating needle valve 60 13 can locate itself automatically and operates automatically with the diaphragm and moreover it is so constructed that its apex never falls below the valve seat in the movements of the diaphragm. Further, as the 65 diaphragm can be a full or integral piece

without any rivetting or fixing the needle thereto, there is no risk of leakage taking place through the diaphragm. The diaphragm being made of phosphor bronze will also resist more effectively the corroding 70 action of the artificial silk spinning solutions.

It has been found that with a diaphragm valve constructed in accordance with the invention it is possible to maintain a uniform rate of delivery under a very wide range or variation of pressure or resistance. Thus in arrangements of the kind described in the said British Patent 182154 it has been found that with the improved diaphragm valve it is possible to work and maintain a uniform debit from the second or measuring pump against considerably greater pressures or resistances such as may build up or occur in the delivery of the 85 solution.

What I claim and desire to secure by Letters Patent is:

1. In artificial silk spinning apparatus employing main and measuring pumps of different deliveries, a horizontally arranged regulating valve apparatus comprising a chamber having an upper wall provided with an outlet, a horizontal valve supporting member dividing the chamber into two 90 portions, and a loose valve member controlling said outlet and supported by but separate from the valve supporting member.

2. In artificial silk spinning apparatus employing main and measuring pumps or different deliveries, a horizontally arranged regulating valve apparatus comprising a chamber having an upper wall provided with an outlet, a horizontal diaphragm dividing the chamber into two portions, and a loose valve member controlling said outlet and supported by but separate from the 100 diaphragm.

3. In artificial silk spinning apparatus employing main and measuring pumps of different deliveries, a horizontally arranged regulating valve apparatus comprising a chamber having a domed upper wall provided with an outlet, a horizontal diaphragm dividing the chamber into two portions, and a needle valve member controlling said outlet and supported by but separate from the 110 diaphragm.

4. In artificial silk spinning apparatus employing main and measuring pumps of different deliveries, a horizontally arranged regulating valve apparatus comprising a chamber having a domed upper wall provided with an outlet, a member dividing the chamber into two portions, and a valve controlling said outlet and supported by said member.

5. In artificial silk spinning apparatus employing main and measuring pumps of different deliveries, a horizontally arranged 130

- regulating valve apparatus comprising a chamber having a domed upper wall provided with an outlet, a horizontal diaphragm dividing the chamber into two portions, a loose valve member controlling said outlet and supported by but separate from the diaphragm, and a spring fitted between the loose valve and the wall of the chamber adjacent said outlet.
- 10 6. In artificial silk spinning apparatus employing main and measuring pumps of different deliveries, a horizontally arranged regulating valve apparatus comprising a
- chamber having an upper wall provided with an outlet, a horizontal diaphragm dividing 15 the chamber into two portions, an inlet for fluid under low pressure in the upper portion of said chamber, an inlet for fluid under high pressure in the lower portion of said chamber, a loose valve member supported by said diaphragm and controlling said outlet, and a spring associated with said valve member.
- In testimony whereof I have hereunto subscribed my name.

FREDERICK TROUTON SMALL.
